CLAIM

The ornamental design for a monitor for a computer, as shown and described.

DESCRIPTION

1. Monitor for computer

1.1 : Front perspective view of our new design, showing the monitor for a computer in a flattened configuration

1.2 : Rear perspective view thereof

1.3 : Front view thereof

1.4 : Rear view thereof

1.5 : Left view thereof

1.6 : Right view thereof

1.7 : Top view thereof

1.8 : Bottom view thereof

1.9 : Front perspective view showing the monitor for a computer in a partially curved configuration

1.10 : Rear perspective view thereof

1.11 : Front view thereof

1.12 : Rear view thereof

1.13 : Left view thereof

1.14 : Right view thereof

1.15 : Top view thereof

1.16 : Bottom view thereof

1.17 : Front perspective view showing the monitor for a computer in a fully curved configuration

1.18 : Rear perspective view thereof

1.19 : Front view thereof

1.20 : Rear view thereof

(Continued)

1.21 : Left view thereof

1.22 : Right view thereof

1.23 : Top view thereof

1.24 : Bottom view thereof

The broken lines indicate portions of the article that form no part of the claimed design.
